UNITED STATES PATENT OFFICE

GEORGE E. PELTON, OF HARTFORD, CONNECTICUT

SUPPLYING INK TO INKING RIBBONS

Application filed March 7, 1930. Serial No. 433,956.

This invention relates to typing machines, and particularly to means for supplying ink to the inking or writing ribbons of such machines while in use.

5 Inking ribbons now in use have two serious faults: they cannot produce clear, sharp and uniform impressions throughout their life; and this life, at best, is a short one, necessitating frequent ribbon replacements.

10 It is the universal experience of those using typewriters that the first impressions from a new ribbon are too black and heavy, the characters are not clear, and it is difficult to erase without smudging. After the ribbon has been in service for several days, or a week—the actual time depending upon the extent and character of use and the original ink content of the ribbon—the excess ink is eliminated and the ribbon begins to produce

15 satisfactory writing. But no sooner is this happy condition attained than the ribbon, because of continued depletion of the ink supply, becomes incapable of producing a clear and legible impression, the characters are reduced to pale wreaths of their former selves, and the ribbon must be discarded. Thus the common typewriter ribbon gives satisfactory results for not more than half its all too short life.

20 The reason for this is that inking ribbons in use today are intended to perform and must perform two functions. Their first and primary function is to convey ink to the type, but their secondary, and no less important function from a practical point of view, is to act as supply reservoirs for that ink. No ribbon can perform both of these functions efficiently and the result is a compromise. The ribbon carries more ink at the outset than it should were excellence of impression the sole desideratum, but not so much as it should were long life the consideration of paramount importance. It is indeed possible, as is sometimes done, to make a ribbon having so little ink that its first impressions are of the proper weight and color, but such a ribbon must be discarded so soon that its use is not practicable under average operating conditions. To go to the other extreme is out of the question. It is not

commercially possible to make a ribbon carrying enough ink for several months' normal use no matter how willing a manufacturer might be to sacrifice the quality of the first impressions. The practical result is a short-lived 55 ribbon producing unsatisfactory, though perforce, passable impressions during the first and last periods of its use. Furthermore, when the common inking ribbon is used in the common way the type must always strike into the ink supply carried by the ribbon in excess of immediate requirements. This causes fouling of the type, particularly when the ribbon is fresh and filled with ink, necessitating frequent cleaning of the type faces 60 and impairing the quality of the typing.

65 It is, therefore, the object of the present invention to overcome these objectionable features inherent in the use of present day inking ribbons to the end that clean, sharp impressions, not too heavy and not too light, may be uniformly produced throughout the life of the ribbon, the length of that life being determined primarily by the ability of the fabric to withstand wear and tear and not by its ink-carrying capacity. I have attained this object, in general, by the use of an inked secondary ribbon extending adjacent the inking ribbon proper—or writing ribbon as I shall call it for sake of clearness—and movable with it, serving as an ink reservoir which continuously gives up its ink to the writing ribbon and maintains the ink content of the latter substantially constant and of the proper value. In this way the 70 writing ribbon is confined to its own proper function of conveying ink to the type, while the other ribbon carries the ink reserve; thus the writing ribbon carries just enough ink to produce the desired quality of impression and 75 its efficacy is unimpaired by a burden of excess ink. Moreover, as the ink content is maintained at the optimum value the impressions do not become progressively lighter as the writing ribbon gives up its ink.

80 85 90 95 100 This secondary or ink-supplying ribbon does not contact with the type and foul them with excess ink, it merely carries a reserve of ink which it feeds to the writing ribbon as the latter gives up its supply in typing. Only

the lightly inked writing ribbon, passing between the type and the surface to be typed, is struck by the type, and it carries too little ink to foul them. In order that the supply ribbon shall not be struck, I preferably separate the two ribbons before the writing ribbon passes the point of impact, guiding the supply ribbon behind the type and out of the way. I have, however, successfully employed a narrow supply ribbon which remains always in contact with the writing ribbon but passes the impact point below the level of the type at that point.

It has been proposed to equip typing machines with small inking pads contacting with the inking ribbon and serving as reservoirs of ink. Experience has shown, however, that the ink supplied by such pads cannot be regulated, as it must be for successful commercial operations, and such pads, if effective at all, transfer far too much ink to the ribbon. So far as I am aware no such auxiliary inking pads are in use today. I have discovered that by employing an inked secondary ribbon to furnish ink to the writing ribbon and interwinding the two upon the same spools, a relatively light contact over an extended area is provided, just sufficient to insure the proper transfer of ink from the supply ribbon to the writing ribbon as the ink content of the latter is depleted.

In my Patent No. 1,732,187, I have described and claimed an inking—or writing—ribbon having an ink-retarding face portion designed to contact with the surface to be typed, and an ink-absorbent body portion. The ink-retarding face comprises a film coating of a cellulose ester, which serves, after drying, as a screen to retard the passage of ink from the ribbon under the impact of the type. As I have pointed out in that patent, the use of such an ink-retarding coating conserves the ink supply and produces a clean and uniform impression over a much longer period than is possible with typewriter ribbons now in common use; nevertheless a time comes when the original ink supply is depleted, the impressions become too faint, and the ribbon must be discarded. But when such a coated writing ribbon is used in connection with the ink-supply ribbon of the present invention, its ink supply is not depleted, and the impressions do not become faint, because as the writing ribbon gives up its ink in typing, fresh ink from the supply ribbon takes its place; this constant renewal maintaining the ink content of the writing ribbon at its original value for an astonishingly long time—at least six to nine months with a ribbon of standard length under average operating conditions—which is more than twice the service which the same coated ribbon could give without the ink-supplying ribbon. Thus, the present invention makes possible a much more efficient use of

the ribbon of my earlier patent, and this I consider one of its most important features. This is not to say that an uncoated writing ribbon might not be used in combination with a supply ribbon, but the advantages inhering in the use of a coated writing ribbon are so great that the use of any other is not recommended.

Only two factors determine the effective life of the ink-regulating writing ribbon of my patent when used in combination with the ink-supplying ribbon of the present invention, and they are: the toughness or wear-resistance of the writing ribbon fabric, and the quantity of ink carried by the supply ribbon.

Now when the writing ribbon is relieved of performing its secondary function of providing an ink reserve and is built for the sole purpose of performing its primary function of transmitting to the type just sufficient ink for the best impression, it is possible to increase its toughness and resistance to type impact and at the same time improve the quality of the impressions made by its use. Thus, when a constant supply of ink is at hand the relative thickness of the ink-retarding face of the ribbon can be measurably increased at the expense of the absorbent and ink-carrying body portion. The degree of penetration of the coating depends upon well understood and controllable factors such as the nature of the fabric, the viscosity of the cellulose solution, and the time during which the coating liquid is permitted to contact with the ribbon, as explained in my pending application, Serial No. 337,820, and so can be increased when desired. I have experienced no difficulty in forcing the ink through this heavier ink-retarding section of the ribbon, while its presence greatly increases the toughness of the ribbon, and in consequence its life. Furthermore, I can employ a fabric chosen for its toughness and general excellence rather than its absorptivity, such as long-fibre natural silk, a fabric quite unsuited for single ribbon use because it is incapable of holding much ink, but admirably adapted for use in connection with a supply ribbon because of its great toughness and its ability to take a heavy cellulose coating. In addition long fibre silk produces a neater impression than spun silk or cotton or any other fabric which has been proposed or used in typewriting, and doubtless would be used in present commercial practice were it possible for it to carry an adequate ink supply. My supply ribbon relieves it of this necessity.

Although I consider a fabric of long-fibre natural silk to be the best for the purpose, other fabrics can be used with satisfactory results. Thus the writing ribbon can be of spun silk, as specified in my patent, or of a combination of silk and cotton, the silk

threads constituting the warp and the cotton the filling, or even of cotton alone, although an all cotton ribbon is inferior to one of silk or silk and cotton.

The other factor determining the effective life of my writing ribbon is the quantity of ink carried by the supply ribbon. As the type do not strike the supply ribbon it can be chosen for its ink-absorbing qualities alone, and much heavier ribbons used than would be possible were they to act as writing ribbons as well as carriers of ink. Thus the actual quantity of ink carried can be determined with reference to the nature of the impression desired.

For letter writing and calculating machine work, a common cotton ribbon, such as is in every day use for writing purposes, and carrying the same initial quantity of ink, serves admirably as the supply ribbon and will furnish adequate ink for from six to nine months. Spun silk or even paper may also be used for this class of work. For making heavy impressions, such as are required for writing checks, an all wool ribbon which will absorb much more ink than the ordinary cotton ribbon can be used. The wool may be woven or felted, or felted on a woven base. For bold work such as the recording of deeds, where bold neat impressions are required, but less ink than in check writing, combinations of wool with cotton or silk may be employed to advantage, the cotton or silk threads forming the warp of the ribbon and the wool the filling. A plural or multi-ply ribbon may also be used, holding ink between the plies.

Although the use of an ink-carrying supply ribbon alone is sufficient to prolong substantially the efficient life of the writing ribbon, I have found that an even longer life can be attained by the use of an ink reservoir for the supply ribbon itself. Moreover by regulating the feed of ink from the reservoir to the supply ribbon I can control the ultimate ink content of the writing ribbon and in that way determine the weight and color of the impressions which any given machine will produce. Thus, as the supply ribbon is unwound from one spool and rewound upon the other during normal machine operation I have produced satisfactory results by passing it in contact with an inking pad which continuously renews the ink in the supply ribbon, the rate at which this renewal takes place being determined by the permeability of the inking surface of the pad. In this arrangement the supply ribbon acts as an ink carrier between the pad and the writing ribbon, nicely controlling the quantity of ink thus transferred. When such an inking pad is employed the ink-carrying capacity of the supply ribbon need not be so great as when no pad is used. Thus a rubberized fabric might be used as the supply ribbon in connection with an inking pad.

As the writing and supply ribbons are interwound upon the same spools with the coated face of the former contacting with the latter it is important that the ink from the supply ribbon should not offset on the cellulose coating and be transferred to the paper. With ordinary care in inking the supply ribbon no such offsetting will occur, but if very thin inks are used there may be a danger from this source. In order to obviate it I can employ a coated supply ribbon so interwound with the writing ribbon that the coated faces of the two are in contact. In this way the coated face of the inking ribbon which contacts with the paper to be typed is brought into contact with the clean coated face of the supply ribbon. The ink is, therefore, fed to the inking ribbon through its uncoated back and the coated face remains relatively dry and clean. As no ink should pass through the coated face of the supply ribbon, I prefer to make this face impervious to ink. As an alternative to a coated supply ribbon I may interpose a strip of celluloid, or other light flexible impervious material, between the writing and supply ribbons.

It is quite possible to adapt existing typewriters to take the double-wound spools of the present invention. The writing ribbon passes from spool to spool and behind the type guide in the usual manner. The supply ribbon also passes from spool to spool but extends across the machine on the keyboard side of the type. Where spool housings are employed, openings must be made for the supply ribbon, and some means should also preferably be provided for guiding that ribbon from spool to spool. Where an inking pad is used I mount it between the spools at the front of the machine frame and draw the supply ribbon across it.

In the accompanying drawings I have illustrated two preferred embodiments of my invention as applied to two different makes of typewriter. In these drawings Figure 1 is a plan view, partly in section, of part of an Underwood noiseless typewriter equipped with the writing and ink-supplying ribbons of the present invention; Figure 2 is an end view of the upper forward part of the machine illustrated in Figure 1; Figure 3 is an enlarged sectional detail taken along line 3-3 of Figure 1; Figure 4 is a plan view similar to Figure 1 showing a Royal typewriter equipped with a supply ribbon and an inking pad; Figure 5 is a transverse section taken along line 5-5 of Figure 1; Figure 6 is an enlarged transverse section through the inking pad and the supply ribbon, and Figure 7 is an enlarged section taken through the writing and ink-supply ribbons as they are wound together on the ribbon spools, both ribbons being shown coated.

Fig. 8 is a fragmentary vertical fore and aft sectional view taken on the line 8-8 of

Fig. 10 and more fully illustrating the ribbon mechanism of the Royal machine provided with the improvements shown in Figs. 4, 5 and 6, the ribbon feeding mechanism being shown as it appears while driving the right hand spool and unwinding the ribbons from the left hand spool, the latter spool being shown in this view;

Fig. 9 is a detail plan view looking down on the said Royal machine from the rear, and showing the ribbon feeding mechanism as it appears at the instant of coupling the left hand spool to the common driving means to reverse the feed of the ribbons;

Fig. 10 is a fragmentary vertical section on the line 10—10 of Fig. 8, showing the parts as positioned after part of the first turn of the right hand spool immediately following shifting of the common driving means from driving connection with the left hand spool into driving connection with the right hand spool;

Fig. 11 is a section on the line 11—11 of Fig. 10; and

Fig. 12 is a detail view similar to Fig. 8, with some of the parts of the Royal machine omitted, and showing part of the ribbon feeding mechanism as it appears at the instant of coupling the common driving means to the left hand spool, as in Fig. 9.

The typewriter illustrated in Figures 1, 2 and 3 comprises a frame 1 on which are mounted the usual carriage carrying a platen 2, and a bank of type 3. Mounted upon the top of the frame 1 on either side of the type 3 are two ribbon spools 4 rotatably mounted upon pins 5. When in use the spools are enclosed within their respective housings or guards 6 each of which is provided with a peripheral opening 8. Wound upon these spools is an inking or writing ribbon 7 which in passing from one spool to the other extends through the openings 8 and is threaded behind the ribbon guide 9. The paper 10, or other material to be typed upon, is wound about the platen in the usual way and passes between the ribbon and the platen at the point of impact of the type. During the operation of the machine the ribbon is slowly unwound from one spool and wound upon the other and then rewound, all in the usual way. The type mechanism is enclosed within a hood or casting 11. The foregoing is a very brief description of parts of a standard Underwood noiseless typewriter and of itself forms no part of the present invention.

In accordance with the present invention I provide an ink-supply ribbon 12 interwound upon the spools with the writing ribbon 7. The writing ribbon is provided with a coating of a cellulose ester on the side contacting with the paper and the supply ribbon may be of any of the materials which I have already specified. Within and just behind the front wall of the type casting 11 I have mounted an arcuate guide plate 13

spaced to permit the passage of the supply ribbon, as illustrated most clearly in Figure 3. The supply ribbon enters the space between the guide plate and the front wall of the casing through end wall openings 14 and extends into the spool housings through peripheral openings 15. Between each of the openings 14 and 15 I have mounted a guide clip 16 provided with a horizontal slot 17 by means of which the ribbon can be inserted into the clip edgewise.

To mount the ribbons on the machine, the double wound spool is placed upon one of the pins 5 and the writing ribbon threaded through the openings 8 and behind the type guide 9 in the usual manner. The casing 11 having first been removed, the supply ribbon 12 is passed through opening 15, inserted in the first guide clip 16, laid around the guide plate 13 and passed through the second guide clip 16 and opening 15 to the writing ribbon. The forward ends of the two are then secured to the empty spool in the usual manner. In ordinary typewriter operation the spool being wound is positively driven and the spool being unwound rotated by means of the unwinding ribbon itself. In order to relieve the supply ribbon of as much strain as possible I prefer, when using the two ribbons of the present invention, to effect the unwinding by means of the writing ribbon alone, as in ordinary single ribbon operation. In order to insure this mode of operation I leave a slight amount of slack in the supply ribbon when the two are secured to the winding spool. The drag exerted upon the supply ribbon by the arcuate guide plate 13 will be sufficient to maintain taut that section of the ribbon extending from the winding spool to the guide plate, whereas the corresponding section between the other end of the guide plate and the unwinding spool will be slack. In Figure 1 the left-hand spool is the winding spool and the slack is shown adjacent the right-hand spool.

Once the ribbons are mounted upon the machine, as illustrated in Figure 1, the operation is precisely as though there were no supply ribbon present. As the typing proceeds the writing ribbon is unwound from one spool and wound upon the other, moving in its passage from spool to spool between the type guide and the paper in the usual manner. Simultaneously with this movement of the writing ribbon the ink-supply ribbon is also unwound from one spool and wound upon the other. As only a few inches of the writing ribbon extend between the two spools, by far the greater part of its length is always in intimate contact with the supply ribbon so that there is ample opportunity for the transfer of the ink from the supply ribbon to the writing ribbon, as the ink content of the latter is depleted.

The Royal typewriter illustrated in Figures 4 and 5 comprises a frame 1' on which are mounted a platen 2', type 3', ribbon spools 4' on pins 5' enclosed within housing 6' having peripheral openings 8' and 15'. Wound upon these spools is a writing ribbon 7' which in passing from one spool to the other is threaded behind a ribbon guide 9', and interwound with the writing ribbon is a supply ribbon 12'. The paper 10' is wound about the platen in the usual way. The foregoing parts correspond in general arrangement and function with the correspondingly numbered parts shown in Figure 1. The machine shown in Figures 4 and 5 differs, however, from the machine shown in Figure 1 primarily in the fact that here I have illustrated an inking pad 23 about which the secondary ribbon 12' passes as it is unwound from one spool and onto the other.

In order that the intermittent movement of the ribbon and the feeding of the same from one spool to the other may be clearly understood, the following description of the Royal ribbon mechanism, it is believed, will be sufficient to enable any one versed in the art to understand how the double ribbon is applied to this mechanism:

The left hand spool 31 and right hand spool 32 each has one end of each of the ribbons 7' and 12' attached thereto by the usual fastening ribbon end fastening means 30. Spools 31 and 32 are held respectively on the upper ends of vertical shafts 33 and 34 to turn therewith, which shafts are journaled in the main framework of the machine. A worm gear 35 is fixed on the lower end of shaft 33, and a bevel gear 36 is fixed on the lower end of shaft 34 and is in constant mesh with bevel gear 37 fixed on a transverse shaft 38 journaled in the machine framework. Adjacent the opposite end of shaft 38 and below gear 35, a worm gear 39 is fixed on said shaft. There is a common driving means shiftable for coupling the same with either of the gears 35 and 39.

To positively drive the left hand spool to reel the ribbons thereon, the common driving worm gear 40 is lifted and held in mesh with gear 35 as shown in Figs. 9 and 12; while to similarly drive the right hand spool to reel the ribbons thereon gear 40 is lowered and held in mesh with gear 39, as shown in Figs. 8 and 10. Gear 40 is always driven in the same direction, being fixed on the forward end of a drive shaft 41 having a universal joint connection 42 at its rear end with a stub shaft 43 journaled in the framework. A pinion 44 loose on shaft 43 meshes with gear 45 fixed on the platen carriage driving spring drum 46 which draws the platen carriage 48 to the left through the medium of the usual draw band 55 attached to the drum and carriage. The leftward or letter spacing

movement of the carriage is a step-by-step movement under control of the carriage escapement comprising the escapement wheel 56 controlled by the usual dogs on escapement rocker 57 pivoted at 58 to rock fore and aft, said rocker being normally held as in Fig. 8 by a suitable spring and being tripped on the down stroke of each type key by a tappet 59 on the universal bar frame which strikes the lower end of the rocker. Drum 46, gear 45 and pinion 44 thus rotate slightly at each printing operation to intermittently feed the ribbons. Pinion 44 always turns in the same direction, remaining stationary during rightward or return movements of the carriage, by reason of said pinion being clutched to shaft 43 by the usual one-way driving clutch 47 to drive the shaft only during leftward movements of the carriage.

The universal bar frame 49 swings forward about a transverse shaft 50 from the normal position shown in Fig. 8 on the down stroke of each type key, each of the type bars 51 of the machine being actuated to print by its associated key through the medium of a link 52, which link rocks the universal bar frame forward through the medium of a draw link 53 attached thereto and hooked around the universal rod or bar 54 of said frame.

In Fig. 8 the ribbon feed mechanism is set to drive the left hand spool, upon which the ribbons are shown partly wound. Pivoted on each spool is a ribbon feed reversing trip device comprising an elbow lever 60, the upper arm of which is normally held against the spool barrel, by the convolutions of the ribbons wound about said barrel, to normally hold the lower laterally extending arm of said elbow lever in an inactive position.

The operation of the feed mechanism is not changed by the presence of the added ribbon.

With the parts set as in Fig. 12, when spool 31 becomes substantially full and the last convolution of the interwound ribbons begins to unwind from spool 32, the trip device 60 on spool 32 drops down, and during further unwinding of said last convolution engages and wipes along the front face of a cam extension 61 of an upright arm or lever 62 and rocks said arm rearward. Arm 62 is fixed on the right hand end of a transverse rock shaft 63 journaled in the framework, said shaft having an upright arm or lever 64 fixed on its left hand end and connected by link 65 with the upper arm of a lever 66 pivoted on the framework on pivot 67. The lower arm of lever 66 carries a roller 68 which is moved over a cam 69 (fixed on tiltable drive shaft 41) when arm 62 is cammed rearward by device 60 wiping over cam extension 61 of arm 62. As shaft 41 turns, cam 69 engages roller 68 and forces the forward end of shaft 41 down until worm 40 is disengaged from gear 35 and engaged with gear 39, and the ribbons begin to reel up upon the

right hand spool as shown in Fig. 10, where the first ribbon convolution is being wound on spool 32 and is about to again lift trip device 60 on said spool into inactive position.

When the ribbons are substantially fully wound on spool 32 and substantially fully unwound from spool 31, trip device 60 on spool 31 drops down as shown in Fig. 12 and wipes over the front face of a cam extension 70 (similar to extension 61) formed on the upper arm of an upright lever 71, which lever is also pivoted on the pivot 67 above referred to. The resultant rocking of lever 71 carries a roller 72 on the lower end of said lever under the cam 69, and continued operation of the machine causes cam 69 to raise the forward end of shaft 41 until worm 40 is disengaged from gear 39 and engaged with gear 35, as shown in Fig. 12, thus again reversing the direction of feed of the ribbons.

The upper ends of arm 62 and lever 71 are normally yieldably held forward by springs 73 and 74, respectively, against parts 75 and 76, respectively, of the main framework of the machine, in which position the raised trip devices 60 on the spools travel above the cam extensions 61 and 70 during rotation of the spools, as indicated in the case of the trip device on spool 32 in Fig. 9 and the trip device on spool 31 in Fig. 8. In Figs. 9 and 12 trip device 60 on spool 31 is shown lowered and bearing against the front face of cam extension 70, in the position of these parts at the completion of coupling the worm 40 to drive the spool 31.

Tilttable drive shaft 41 is yieldably latched in each of its two spool driving positions by an automatic latch. A bell crank lever 78 pivoted at 79 on the machine framework has shaft 41 journalled in its laterally extending arm and has a roller 80 on its upwardly extending arm. Roller 80 during the raising and lowering of shaft 41 snaps to opposite sides of cam nose 81 on the upper edge of latch arm 82, which arm is pivoted on the framework at 83 and yieldably held up by spring 84.

The writing ribbon 7', in passing from spool to spool, is threaded as usual through the usual ribbon vibrator or reciprocatory ribbon guide 85 slidably guided on the usual fixed type guide 86 to reciprocate vertically at the rear of the type guide, from the normal lowered position uncovering the printing point shown in Fig. 8, to a raised position in which the ribbon 7' covers the printing point on the front of platen 2'. The vibrator 85 is pivoted at its lower end to the forwardly extending arm of a bell crank lever 87 pivoted on the usual carriage supporting framework 88 at 89 and normally held in the position shown in Fig. 8 by spring 90. To lift the vibrator and interpose the writing ribbon as usual between the type and platen 65 when a type bar 51 makes its printing stroke,

the pendent arm of bell crank 87 is pivoted to a fore-and-aft reciprocable actuating bar 91 the front end of which is suspended from framework 88 by link 92 and the rear end of which is engaged and pushed forward, on the printing stroke of each type bar, by a tappet 93 that moves forward and rearward with the universal bar frame 49.

To prevent any possible accidental reverse rotation of worm 40 and shaft 41 during return or rightward movements of the platen carriage, a ratchet wheel 94 fixed on said shaft is held against reverse rotation by a spring-pressed pawl 95 pivoted on bell crank 78, as usual.

This inking pad 23 comprises a segment-shaped piece of felt mounted upon the top of the frame and secured in position by means of screws 24. It is saturated with ink and provided with an ink-retarding covering 27 along its outer and ribbon-contacting surface. This covering may be a coated fabric identical with or similar to the writing ribbon itself placed with its coated face outermost. The ink fed from the pad to the ink-supplying ribbon must pass through this fabric which must therefore be pervious to ink. The rate at which the ink passes from the pad to the supply ribbon is determined by the permeability of the pad fabric and this affords me a means for controlling the ultimate ink content of the inking ribbon. Thus for a typewriter equipped with pica type for letter writing I cover the inking pad with a fabric heavily coated with pyroxylin or with a plurality of coated fabrics so that relatively little ink is picked up by the supply ribbon. On the other hand, a machine equipped with Gothic type for billing and similar heavy work should have a pad covered with but a single thickness of a lightly coated fabric permitting of a heavy ink discharge. In any case, however, the amount of ink carried by the writing ribbon is constant so that the weight and color of impression decided upon shall be maintained uniform as long as desired.

In Figure 7 I have illustrated both the writing ribbon 7' and the supply ribbon 12' provided with an ink-retarding coating 26 comprising pyroxylin, as described in my Patent No. 1,732,187. The coated face of the writing ribbon faces the platen and so contacts with the paper during typing, the ink being forced from the ribbon through the coating by the type. The uncoated side of the ink-supplying ribbon yields the ink, and where a pad is used this uncoated side passes across the inking pad 23 and absorbs ink therefrom. When the two ribbons come together, as they do when wound upon the spools, their uncoated faces are in opposition and contact with each other. By virtue of this arrangement the ink carried by the supply ribbon is transferred directly to the uncoated and ab-

- sorbent body portion of the inking ribbon. Moreover, as the two coated faces are outermost they contact, during winding, with each other only, thereby preventing the offsetting of ink on the paper contacting side of the ribbon. Figure 7 is only diagrammatic. It must not be considered as accurately illustrating the relations between the coating and the fabric of the ribbon.
- 10 Although I have illustrated a pad as a suitable means for supplying ink to the supply ribbon, other means such as rollers contacting with both an ink supply and the supply ribbon might be used.
- 15 Among the many advantages inherent in the improvements of the present invention, the following may be noted:
- Uniform excellence of type impression can be had over a period of use longer than is otherwise possible with the best equipment now available.
- The effective ribbon life is increased many fold thereby avoiding frequent changings.
- Any character of impression desired can be had, and once chosen can be uniformly produced.
- As the type do not strike into the ink supply, fouling is minimized and cleaning of the type becomes infrequent.
- 30 Strong, tough, heavily coated fabrics such as long fibre natural silk, capable of producing the clearest and best impressions can be used as the writing ribbon despite the fact that such fabrics are incapable of carrying more than a very small quantity of ink.
- The present invention was conceived primarily for use in connection with typewriter ribbons and will doubtless find its largest field of usefulness there, but in its broader aspects it is clearly applicable wherever the problem arises of obtaining an ample, continuous and uniform ink feed from an inking ribbon, as in weighing machines, multi-graphing machines, adding and accounting machines, cash registers, time recorders, and all typing or printing machines in which ink for the impression is furnished by a ribbon interposed between the surface typed upon and the type.
- 50 I claim:
1. A method of operating a writing machine comprising feeding a writing ribbon back and forth past the common writing point, forcing ink step by step from a part of said ribbon as each type strikes the ribbon while maintaining said writing ribbon and an ink supply ribbon in ink transfer effecting contact.
  2. The method of keeping a supply of ink in a writing ribbon which comprises maintaining said writing ribbon, in ink transfer effecting contact, with an ink supply ribbon.
  3. The method of operating a writing machine which comprises maintaining two

ribbons in contact, and separating said ribbons when the writing ribbon passes to the writing point without bringing the ink supply ribbon in contact with the type.

4. Ink supply means for use in writing machines including ribbon feed spools, suitable ribbon guides, a writing ribbon, an ink supply ribbon, said ribbons being interwound by rotation of the spools, the writing ribbon being capable of renewing its ink supply by absorption while interwound with the ink supply ribbon.

5. Ink supply means for use in writing comprising a feed spool, a writing ribbon fastened to said spool and an ink supply ribbon almost entirely interwound with the said writing ribbon and said ribbons carrying ink.

6. In a printing apparatus having impression forming means, a writing ribbon, apparatus for presenting said ribbon for ink expulsion therefrom at a different point in its length at each typing operation of the apparatus, the combination with said ribbon of an ink supply ribbon associated therewith for transfer of ink to each portion of the writing ribbon from which ink is expelled.

7. In a printing apparatus having impression forming means, a writing ribbon, and means for presenting said ribbon for ink expulsion therefrom at a different point in its length at each impression forming operation of the apparatus, the combination with said ribbon of an ink supply ribbon associated therewith for direct transfer of ink from the latter ribbon to the writing ribbon substantially throughout the length of the writing ribbon at all times without presenting the ink supply ribbon for ink expulsion therefrom by the typing apparatus.

8. In a printing apparatus having impression forming devices, an impression writing ribbon from which ink is expelled by impression forming actions of said devices, and ribbon controlling means presenting said ribbon for ink expelling action thereon by said devices, progressively, substantially from end to end of the ribbon and back again alternately, the combination with said devices, ribbon and means, of a flexible ink carrier supplying ink to said writing ribbon, and contacting with same, substantially from end to end.

9. A printing apparatus having an ink supply ribbon, a writing ribbon capable of absorbing ink from the ink supply ribbon, spools with which said ribbons are connected for interwinding of the said ribbons face to face on either spool, typing means coactive with the writing ribbon, and means coactive with the ink supply ribbon as it extends from spool to spool permanently withholding the ink supply ribbon from the field of action of said typing means.

10. In a typewriting machine having key-

controlled type movable to the common printing point, the combination with said types of means for forming the type impressions comprising two ribbons carrying ink, a pair of ribbon feed spools with which said ribbons are connected for reeling of the ribbons upon first one spool and then the other with the ribbons in direct ink-transfer effecting face contact while wound on the spools, and means for presenting one of said ribbons at the common printing point and holding said other ribbon out of the path of the types.

11. A typewriting machine of the kind wherein a writing ribbon carrying ink is presented at the printing point for expulsion of ink by type and is reeled step by step for substantially its full length first on one and then on the other spool, and wherein is provided a supply ribbon which interwinds with the impression writing ribbon on each spool without the ink supply ribbon being acted upon by the types during operation of the machine.

12. A typewriting machine having types controlled to write at the common printing point, two ribbons carrying ink, and means controlling said ribbons for ink expulsion by the type at the common printing point solely from the writing ribbon and for ink extraction by absorption by the writing ribbon from the ink supply ribbon, including means for feeding the ribbons in unison.

13. The combination of a writing ribbon for transferring ink to a writing surface, an ink supply ribbon of absorbent material and impregnated with an ink of a consistency enabling it to pass slowly by capillary absorption to said writing ribbon when contacting therewith, and means for bringing different portions of said writing ribbon into contact with said supply ribbon for substantial intervals of time to cause said supply ribbon to replenish ink transferred from said writing ribbon to a writing surface.

14. The combination of a pair of ink ribbons, one of which serves to transfer ink to a writing surface and the other of which supplies ink to the first mentioned ribbon when contacting therewith for substantial intervals of time.

15. The combination of a writing ribbon which serves to transfer ink to a writing surface, and an ink supply member of absorptive material carrying a supply of ink, said writing ribbon contacting with said supply member during substantial intervals of time to supply ink to the transfer member by capillary absorption.

16. The combination of a writing ribbon which serves to transfer ink to a writing surface and an ink supply member of absorptive material carrying a supply of semi-liquid slow flowing ink, and means for bringing said writing ribbon into contact with said

supply member during substantial intervals of time sufficient to enable said slow flowing ink to pass from said supply member to said writing ribbon by capillary action.

17. In a typing machine, the combination of a writing ribbon, and flexible ink supplying means movable with the writing ribbon, for supplying ink to said ribbon while in use in predetermined quantity for any size or style type. 75

18. In a typing machine, the combination of a high thread count, thin, long wear writing ribbon and a cheap grade low thread count ink supplying ribbon contacting with the writing ribbon and feeding ink thereto in predetermined quantity while the writing ribbon is in use for any size or style type. 80

19. An ink pad including a base portion of a material capable of carrying ink, and a coating associated therewith for retarding the flow of ink therethrough from said base to type or ribbons, or other articles. 85

20. An ink pad including a base portion of a material capable of carrying ink and having a surface thereof exposed to deliver ink, and a coating associated with said surface to control the passage of ink therethrough to type or ribbons, or other articles. 90

21. An ink pad including a base portion of a material capable of carrying ink, said pad having associated with the exposed surface a composition permeable to ink and through which the ink passes from the base to type or ribbons, or other articles, said composition retarding excessive passage of ink therethrough. 95

22. An ink pad including a base portion of a material capable of carrying ink, said pad having a cellulose composition permeable to ink associated with the exposed surface thereof and which permits a restricted flow of ink from said base to type or ribbons or other articles contacting with said exposed surface. 105

23. An ink pad including a base which is capable of carrying ink, a thin cover through which ink may pass, a composition permeable to ink and applied to said cover, and through which ink may pass from the base in a restricted manner to type or ribbons or other articles. 110

24. An ink pad including a base which is capable of carrying ink, and a covering material contacting with said base and impregnated with a composition permeable to ink, and regulating as desired the amount of ink passing therethrough. 115

25. An ink pad including a base which is capable of carrying ink, and a covering material which is arranged on a portion of said base and permeable to ink and which is impregnated with a composition so as to cause the material to act as a screen or filter and retard the passage of ink through said material. 125

26. An ink pad comprising an ink-carrying 130

base and a chemical coating associated therewith regulating the passage of ink from said base.

27. An ink pad comprising an ink-carrying base and an ink-pervious chemical coating on the operative face of the pad through which the ink is passed in restricted amounts to articles contacting therewith.

28. An ink pad comprising an ink-carrying base and an ink-pervious coating of a cellulose ester associated therewith regulating the passage of ink therethrough.

29. An ink pad comprising an ink-carrying base and an ink-pervious covering coated with a cellulose ester on the operative face of the pad through which the ink is passed in restricted amounts to articles contacting therewith.

30. In a typing machine, the combination of a writing ribbon, and an ink-supply ribbon contacting with the writing ribbon throughout the major portion of its length and feeding ink to it.

31. In a typing machine, the combination of a writing ribbon carrying the optimum quantity of ink for the character of impression desired, and an ink-supplying ribbon contacting with the writing ribbon and feeding ink to it while in use in order to maintain the ink content of the writing ribbon at the predetermined optimum value.

32. In a typing machine, the combination of a writing ribbon, means for moving the writing ribbon to present a fresh area to the type, and an ink supply ribbon contacting with the ink ribbon and movable with it.

33. In a typing machine, the combination of a writing ribbon, a ribbon for supplying ink thereto, spools upon which the two ribbons are interwound, means for unwinding the ribbons from one spool and winding them upon another during the operation of the machine, the writing ribbon in its passage from one spool to another being interposed between the type and the surface to be typed, and means for guiding the ink supply ribbon away from the type and the surface to be typed as it passes from one spool to the other.

34. A typing machine comprising the combination of a bank of type, a platen for supporting the paper or other material to be typed, mechanism for causing the type to strike against the paper, a writing ribbon interposed between the paper and the type at the point of impact, spools upon which the ribbon is wound, mechanism for unwinding the ribbon from one spool, moving it past the point of impact and winding it upon another spool, and an ink supply ribbon interwound with the writing ribbon likewise moved from one spool to another but not between the paper and the type at the point of impact.

35. In a typing machine, the combination of spools, a writing ribbon and an ink supply ribbon interwound on said spools, and

70 housings for the spools, each spool housing having two peripheral openings, one for the writing ribbon and one for the ink-supply ribbon.

36. In a typing machine, the combination of a writing ribbon having an absorbent body portion and an ink-retarding face portion, and means for supplying ink to the absorbent body portion of the writing ribbon while in the machine.

75 37. In a typing machine, the combination of a writing ribbon having an absorbent body portion and an ink-retarding face portion of a cellulose ester, means for supplying ink to the absorbent body portion of the writing ribbon while in the machine.

80 38. In a typing machine, the combination of a writing ribbon having an absorbent body portion and an ink-retarding face portion, means for moving the writing ribbon between the type and the surface to be typed with the ink-retarding face portion adjacent the surface to be typed, and means for supplying ink to the absorbent body portion of the writing ribbon while in use in the machine.

85 39. In a typing machine, the combination of a writing ribbon having an absorbent body portion and an ink-retarding face portion, means for moving the writing ribbon between the type and the surface to be typed with the ink-retarding face portion adjacent the surface to be typed, and an ink supply ribbon contacting with the absorbent body portion of the writing ribbon and movable therewith.

90 40. In a typing machine, the combination of a writing ribbon having an ink-retarding face portion, and an ink-supply ribbon interwound with the writing ribbon and feeding ink to it.

100 41. In a typing machine, the combination of a writing ribbon having an ink-retarding face portion, an ink-supply ribbon interwound with the writing ribbon and feeding ink to it, and means preventing the transfer of excess ink from the ink-supply ribbon to the ink-retarding face of the writing ribbon.

105 42. In a typing machine, the combination of a writing ribbon having an absorbent body portion and an ink-retarding face portion, means for moving the writing ribbon between the type and the surface to be typed with the ink-retarding face portion adjacent the surface to be typed, and an ink-supply ribbon likewise having an absorbent body portion and an ink-retarding face portion, the absorbent body portions of the two ribbons contacting with each other.

115 43. In a typing machine, the combination of a writing ribbon carrying the optimum quantity of ink for the character of impression desired, an ink-supply ribbon contacting with the writing ribbon and feeding ink to it while in use in order to maintain the ink content of the writing ribbon at the predetermined optimum value, and an ink

- reservoir which gives up ink to the ink-supply ribbon.
44. In a typing machine, the combination of a writing ribbon, means for moving the writing ribbon to present a fresh area to the type, an ink-supply ribbon contacting with the writing ribbon, and an ink reservoir which gives up ink to the ink-supply ribbon.
45. In a typing machine, the combination of a writing ribbon, means for moving the writing ribbon to present a fresh area to the type, an ink-supply ribbon contacting with the writing ribbon and movable with it, an ink reservoir which gives up ink to the ink-supply ribbon as it moves, and means for controlling the feed of ink from the ink reservoir to the ink-supply ribbon.
46. In a typing machine, the combination of a writing ribbon, means for moving the writing ribbon between the type and the surface to be typed, an ink-supply ribbon contacting with the writing ribbon and movable with it, and an inking pad contacting with the ink-supply ribbon.
47. In a typing machine, the combination of a writing ribbon, means for moving the writing ribbon between the type and the surface to be typed, an ink-supply ribbon contacting with the writing ribbon and movable with it, an ink reservoir which gives up ink to the ink-supply ribbon and an ink-retarding element interposed between the ink-reservoir and said ink-supply ribbon, controlling the feed of ink from the ink-reservoir to the ink-supply ribbon.
48. In a typing machine, the combination of a wound writing ribbon, an ink-supply ribbon interwound with it, an inking pad, and means for unwinding the two ribbons during the operation of the machine, passing the writing ribbon between the type and the surface to be typed and passing the ink supply ribbon over the inking pad.
49. In a typing machine, the combination of a writing ribbon, a ribbon for supplying ink thereto, a pair of spools upon which the two ribbons are interwound, an inking pad, and means for unwinding the ribbons from one spool and winding them upon the other, the writing ribbon in moving from one spool to the other passing between the type and the surface to be typed while the supply ribbon passes in contact with the inking pad.
50. A typewriting machine, comprising the combination of a bank of type, a platen for supporting the paper or other material to be typed, mechanism for causing the type to strike against the paper, a writing ribbon interposed between the paper and the type at the point of impact, an inking pad, an ink-supply ribbon, spools upon which both ribbons are interwound, and mechanism for unwinding the ribbons from one spool and winding them upon another, the writing ribbon moving past the point of impact in its passage from spool to spool while the ink-supply ribbon moves in contact with the inking pad.
51. In a typing machine, the combination of a writing ribbon having an absorbent body portion and an ink-retarding face portion, an ink reservoir, an ink-supplying ribbon likewise having an absorbent body portion and an ink-retarding face portion, the absorbent body portions of both ribbons contacting with each other, and means for moving the writing ribbon between the type and the surface to be typed with its ink-retarding face adjacent the surface to be typed and for causing the ink-supply ribbon to take up ink from said reservoir.
52. In a typing machine, the combination of a writing ribbon having an absorbent body portion and an ink-retarding face portion, an ink reservoir, an ink-supply ribbon likewise having an absorbent body portion and an ink-retarding face portion, the absorbent body portions of both ribbons contacting with each other, means for moving the writing ribbon between the type and the surface to be typed with its ink-retarding face adjacent the surface to be typed and for causing the ink-supply ribbon to take up ink from the reservoir, and an ink-retarding element interposed between the reservoir and the ink supply ribbon controlling the feed of ink from the reservoir to the ink-supply ribbon.
53. A typewriter ribbon spool having wound thereon a writing ribbon carrying relatively little ink and an ink-supplying ribbon carrying a relatively greater quantity of ink interwound with the writing ribbon.
54. A typewriter ribbon spool having wound thereon a writing ribbon of long fibre natural silk and an ink-supplying ribbon contacting with the writing ribbon and feeding ink to it.
55. A typewriter ribbon spool having wound thereon a writing ribbon of long fibre natural silk having an ink-retarding face portion of a cellulose ester and an ink-supplying ribbon interwound with the writing ribbon and feeding ink to it.
56. A typewriter ribbon spool having interwound thereon a writing ribbon and an ink-supplying ribbon.
57. A typewriter ribbon spool having interwound thereon a writing ribbon having an ink-retarding face portion, and an ink-supplying ribbon.
58. A typewriter ribbon spool having interwound thereon a writing ribbon having an ink-retarding face portion of a cellulose ester, and an ink-supplying ribbon.
- In testimony whereof I affix my signature.
GEORGE E. PELTON.
